UNITED STATES PATENT OFFICE

JOHN F. O'CONNOR, OF CHICAGO, ILLINOIS, ASSIGNOR TO W. H. MINER, INC., OF CHICAGO, ILLINOIS, A CORPORATION OF DELAWARE

JOURNAL BEARING

Application filed September 28, 1927. Serial No. 222,416.

This invention relates to journal bearings.

An object of the invention is to provide an antifriction arrangement, more particularly adapted for use in connection with a journal box and a journal of a railway car, and wherein the journal box and journal are provided with suitable conical race members between which are interposed spaced annular series of opposite disposed conical rollers in conjunction with retaining means for said rollers having spherical surfaces adapted to engage spherical surfaces formed at the opposite ends of said rollers whereby the latter are at all times maintained in proper alignment.

Other and further objects of the invention will more clearly appear from the description and claims hereinafter following.

In the drawings forming a part of this specification, Figure 1 is a side elevational view of a fragment of a railway car truck showing a pedestal member and a journal box, embodying the invention, mounted in said pedestal member. Figure 2 is a transverse vertical sectional view corresponding to the line 2-2 of Figure 1. Figure 3 is a vertical sectional view, corresponding substantially to the line 3-3 of Figure 2. And Figure 4 is an enlarged detail view of a roller.

As shown in the drawing, 10 represents a fragment of the body portion of the car truck and 11 represents a common type of pedestal member mounted thereon, having the usual spaced jaws between which is slidably disposed a journal box 12 embodying the invention. The numeral 13 indicates one end of an equalizer bar which bears upon the top of the journal box 12 and transmits the load from the frame of the truck to the top of the journal box which in turn transmits the load to the journal.

The invention broadly contemplates the provision of a journal box A, conical race members B, conical rollers C, and retaining aligning means D.

The journal box A comprises side, top, bottom and rear walls, and is of hollow construction having a centrally disposed annular recess 14 adapted for the reception of the journal 15. The journal 15 projects through an aperture 16 in the rear wall of the journal box, and the edge of the rear wall defining the aperture 16 is provided with a groove 17 for the reception of packing material 18. The top wall of the journal box A is provided with spaced flanges 19-19, and an equalizer seat 20 adapted to be engaged by the grooved end of the equalizer bar 13. The side walls of the journal box A are provided with spaced flanges indicated at 21-21 which fit upon opposite sides of the pedestal box of the pedestal member to provide guides, the journal box A being retained in its position between the jaws of the pedestal member by the usual strap 22. The journal 15 is formed to provide an annular shoulder 23, a cylindrical portion 24, and a reduced threaded end portion 25.

The race members B comprise a sleeve 26 mounted upon the cylindrical portion 24 upon the journal 15, and the two spaced rings 27 and 28 associated with the journal box. The sleeve 26 is slidably but non-rotatably mounted upon the journal 15 by any suitable means, and has its circumferential periphery formed to provide a cylindrical portion 29, and outwardly tapering cone surfaces 30 and 31, the opposite ends of the sleeves being reduced to provide cylindrical portions indicated at 32. The ring 28 is provided with a conical surface 33 adapted to co-operate with the conical portion 31 of the sleeve 26, and said ring is disposed in the annular recess 14 of the journal box A in such manner as to bear upon an annular shoulder 34 formed adjacent the rear wall of the journal box as best shown in Figure 2. The race ring 27 is of a character similar to the race ring 28 but oppositely disposed with reference thereto, and mounted in the recess 14 so as to be

capable of some axial movement for purposes of adjustment as hereinafter referred to. The ring 27 is provided with a tapered surface 35 adapted to co-operate with the conical surface 30 of the sleeve 26.

The conical rollers C are arranged in two annular series 36 and 37, the series 36 being adapted to co-operate with the surfaces 30 and 35 of the ring 27 and sleeve 26, and the annular series 37 being adapted to co-operate with the surfaces 31 and 33 of the sleeve and ring 28. The annular series of rollers 36 and 37 are arranged in spaced relation, and each roller of each series upon adjacent ends is formed to provide a convex spherical surface 38, the spherical surfaces of the inner ends of the rollers being similar in character, and adapted to co-operate with the retaining and aligning means D. The outer or smaller end of each roller of each annular series of rollers is formed to provide a concave spherical surface 380, the spherical surfaces 380 of the rollers also being adapted to co-operate with the retaining and aligning means D.

The retaining and aligning means D comprise a central element 39 and end elements 40 and 41. The central element 39 is disposed between the inner ends of the two annular series of rollers, and includes an annular web 42 of somewhat greater diameter than the cylindrical portion 29 of the sleeve 26, so as to be spaced therefrom, and formed upon the web 42 are spaced angularly disposed flanges 43 and 44, said flanges diverging toward their outer ends and being connected by laterally extending braces. Each of the flanges 43 and 44 is so formed as to provide a concave spherical bearing surface 45 of such curvature as to conform to the curvature of the convex spherical surfaces 38 of the adjacent annular series of rollers C, said spherical surfaces being so formed that the inner end of each of the rollers C is adapted to fit the spherical surface 45 provided by each of the flanges 43 and 44, it being noted that the retaining member 39 is supported by the rollers C in spaced relation with reference to the sleeve 26 on the journal. The retaining members 41 and 410 are exactly similar, except for their opposite disposition. The member 41 is in the form of a ring which fits about the reduced end portion 32 of the sleeve 26 and is spaced therefrom, the surface of the ring 41 being formed with a convex spherical surface 47 corresponding in curvature to the spherical surface 45 of the flange of the central member 39, the convex spherical surface 47 being of such curvature as to fit the concave spherical surface 380 of each of the rollers of the annular series 37. The surface of the member 41 opposite to the spherical surface is provided with an annular groove corresponding with an annular groove formed in a collar 48 mounted upon the jour-

nal 15 and bearing against the annular shoulder 23 thereof, an annular series of balls 49 being disposed in the grooves of the member 41 and collar 48, which balls maintain the member 41 in the desired position and reduce friction between the parts. The member 410 at the outer ends of the annular series of rollers 36, is oppositely disposed with reference to the member 41 but otherwise is identical therewith, having a convex spherical surface adapted for co-operation with the concave spherical surfaces of the ends of the rollers of the series 36. A series of balls 50 is interposed between the outer face of the member 410 and a collar 51 on the journal 15, the balls being disposed in annular grooves in the adjacent surfaces of said members. The collar 50 is held upon the journal by means of a lock nut 52, which serves to maintain the various parts of the arrangement in assembled condition with reference to the journal. A cover 53 is provided for the journal box having a flange 54 adapted to be secured to the journal box by bolts 55, there being a plurality of shims 56 interposed between the flange 54 and the adjacent edge of the journal box. The cover 53 is also provided with an annular flange 57 which telescopically fits within the recess 14 and bears upon the race ring 27. When it is desired to adjust the arrangement, one or more of the shims 56 is removed, bringing about inward axial movement of the ring 27, causing corresponding movement of the sleeve and annular series of rollers to the right, as viewed in Figure 2, thereby adjusting the various elements with reference to each other from the outer end of the journal when the same is in position in the journal box.

By the above described arrangement, it will be appreciated that the spherical surfaces upon the retaining members 39, 41, and 410, co-operating with the spherical surfaces upon the rollers D, will have the effect of positively maintaining said rollers in alignment laterally as well as in other directions. The retaining members 39, 41 and 410 move with the rollers, while the rollers rotate upon their individual axes with reference to said members. The member 39 is carried by the rollers and hence develops no friction with reference to the sleeve on the journal, and the end members 41 and 410 are supported by the anti-friction balls 49 and 50 so that friction between the end members is reduced to the minimum.

While I have herein shown and described what I consider the preferred manner of carrying out the invention, the same is merely illustrative and I contemplate all changes and modifications which come within the scope of the claims appended hereto.

I claim:

1. In a structure of the character described,

- the combination with relatively movable race members, providing oppositely disposed conical bearing surfaces; of an annular series of conical rollers co-operating with each of the oppositely disposed bearing surfaces of said race members, said annular series of rollers being spaced apart, the adjacent inner ends of said rollers being provided with oppositely disposed convex spherical surfaces, and the outer ends of each of said rollers being provided with a concave spherical surface; retaining means interposed between the inner ends of the annular series of rollers, said retaining means having concave bearing surfaces engageable with the convex bearing surfaces of the adjacent ends of said rollers; and additional retaining means associated with the outer ends of each annular series of rollers and being provided with convex spherical bearing surfaces engageable with the concave spherical bearing surfaces of said rollers; and anti-friction means for supporting said additional retaining means in operative condition with reference to said rollers.
2. In a structure of the character described, the combination with relatively movable race members, providing oppositely disposed conical bearing surfaces; of an annular series of conical rollers co-operating with each of the oppositely disposed bearing surfaces of said race members, said annular series of rollers being spaced apart, the adjacent inner ends of said rollers being provided with oppositely disposed convex spherical surfaces, and the outer ends of each of said rollers being provided with a concave spherical surface; retaining means interposed between the inner ends of the annular series of rollers, said retaining means having concave bearing surfaces engageable with the convex bearing surfaces of the adjacent ends of said rollers; and additional retaining means associated with the outer ends of each annular series of rollers and being provided with convex spherical bearing surfaces engageable with the concave spherical bearing surfaces of said rollers; and means for adjusting the race members and rollers with reference to each other.
3. In a structure of the character described, the combination with a journal box and a journal; of a sleeve mounted on said journal and provided with oppositely disposed cone surfaces; spaced race rings associated with said journal box and provided with bearing surfaces co-operating with the conical surfaces of said sleeve to provide raceways for conical rollers; two annular series of conical rollers interposed between said race members, said series of rollers being arranged in spaced relation, each roller of each series having one end concave spherical in form and the opposite end convex spherical in form, the convex ends being disposed in the same direction and arranged in facing relation; a retainer disposed between the inner ends of the annular series of rollers and having oppositely disposed spherical surfaces engageable with the spherical end surfaces of said rollers; and additional retaining rings arranged at the outer ends of said rollers and provided with convex spherical bearing surfaces adapted to co-operate with the concave spherical surfaces of the ends of said rollers.
4. In a structure of the character described, the combination with a journal box and a journal; of a sleeve mounted on said journal and provided with oppositely disposed cone surfaces; spaced race rings associated with said journal box and provided with bearing surfaces co-operating with the conical surfaces of said sleeve to provide race-ways for conical rollers; two annular series of conical rollers interposed between said race members, said series of rollers being arranged in spaced relation, each roller of each series having one end concave spherical in form and the opposite end convex spherical in form, the convex ends being disposed in the same direction and arranged in facing relation; a retainer disposed between the inner ends of the annular series of rollers and having oppositely disposed spherical surfaces engageable with the spherical end surfaces of said rollers; and additional retaining rings arranged at the outer ends of said rollers and provided with convex spherical bearing surfaces adapted to co-operate with the concave spherical surfaces of the ends of said rollers.
5. In a journal bearing for railway cars, the combination with a journal box provided with annular spaced raceways; of an axle rotatable within said journal box, said axle being provided with a bearing sleeve presenting annular raceways opposed to said first named raceways; two annular series of anti-friction rollers interposed between said journal box and axle race-ways; spacing means for said two series of rollers; a retaining ring having shouldered engagement with the axle; a second retaining ring at the outer end of the axle, said retaining rings embracing the two series of rollers; and means for adjusting said last named retaining ring lengthwise of the axle to compensate for wear of the ends of the rollers.
6. In a journal bearing for railway cars, the combination with a journal box provided with annular spaced raceways; of an axle rotatable within said journal box, said axle being provided with a bearing sleeve presenting annular raceways opposed to said first named raceways; two annular series of anti-friction rollers interposed between said journal box and axle race-ways; spacing means between said rollers engaging the inner ends thereof; a retaining ring having shouldered engage-

ment with the axle; a second retaining ring at the outer end of the axle; bearing rings engaging the outer ends of the rollers; anti-friction ball bearing elements interposed between each of said retaining rings and the corresponding bearing ring; and means for adjusting the retaining ring at the outer end of the axle lengthwise thereof, to take up for endwise wear of the rollers and cooperating parts.

In witness that I claim the foregoing I have hereunto subscribed my name this 24th day of September, 1927.
